CLAIM

The ornamental design for a brace holder for gasoline pump flow handle, as shown and described.

DESCRIPTION

FIG. 1 is a perspective view of a brace holder for gasoline pump flow handle showing my new design;
FIG. 2 is a left side elevational view thereof;
FIG. 3 is a front elevational view thereof;
FIG. 4 is a right side elevational view thereof;
FIG. 5 is a back elevational view thereof;
FIG. 6 is a top plan view thereof; and
FIG. 7 is a bottom plan view thereof.

FIG. 1

FIG. 2
FIG. 4

FIG. 3
FIG. 5

FIG. 6

FIG. 7
